DOOR CHECK

Paul H. Travis, Detroit, Mich.

Application September 15, 1939, Serial No. 295,136

15 Claims.

(Cl. 16—86)

This invention relates generally to door checks, i. e., devices for limiting the swinging movement of doors, and refers more particularly to door checks of the concealed type.

5 One of the essential objects of the invention is to provide a door check wherein provision is made for effectively absorbing or cushioning shocks resulting from checking the swinging movements of the doors.

10 Another object is to provide a strong and durable door check that is simple in construction, economical to manufacture, and easy to install.

15 Other objects, advantages and novel details of construction of this invention will be made more apparent as this description proceeds, especially when considered in connection with the accompanying drawing, wherein:

Figure 1 is a fragmentary horizontal sectional view through a swinging door, supporting hinge pillar therefor, and door check embodying my invention, and showing the arrangement of parts when the door is in closed position;

20 Figure 2 is a view similar to Figure 1, but showing the door in open position;

25 Figure 3 is an end view of the door check shown in Figures 1 and 2;

Figure 4 is a detail view of the washer illustrated in Figure 3;

30 Figure 5 is a side elevation of a slightly modified form of door check;

Figure 6 is a fragmentary longitudinal sectional view through the door check illustrated in Figure 5;

35 Figure 7 is an end view of the door check illustrated in Figures 5 and 6;

Figure 8 is a side elevation of another modified form of door check;

Figure 9 is a longitudinal sectional view through the door check illustrated in Figure 7;

40 Figure 10 is an end view of the door check illustrated in Figures 8 and 9.

Referring now to the drawing, A is the head, B is the shank, and C is the shock absorbing or cushioning element of a door check embodying my invention. As shown, the head A and shank B are formed from one piece of relatively heavy spring wire and cooperate to hold the cushioning element C. Preferably the head A comprises the laterally bent end portions 1 and 2 of the wire, while the shank B comprises the elongated return-bent portions 3 and 4, respectively, of the wire. The return-bend of the wire is preferably opened slightly to provide an eye 5 for the reception of a suitable anchorage member such as 6. The cushioning element C is preferably a block

of resilient material such as rubber or rubber composition and is sleeved upon the shank B adjacent the head A. In this construction a washer D is also sleeved on the shank B between the cushioning element C and head A and serves as 5 a tie or coupling between the return-bent portions 3 and 4 of the wire at the free ends of the latter. As shown, the washer D has a central slot 7 of sufficient length to receive the eye 5 when the washer is sleeved upon the shank and 10 is provided in opposite edges of said slot with notches 8 and 9 for receiving the shank portions 3 and 4 of the wire. Preferably the slot 7 and notches 8 and 9 are so formed that the washer D may be turned 90° on the shank B from the 15 position in which the slot 7 received the eye 5 to the position in which the notches 8 and 9 receive the shank portions 3 and 4 of the wire so that the shank portions will be held by the notches in proper relation to each other. 20

In use the door check extends substantially horizontally between the door E and its supporting hinge pillar F. As shown, the anchorage member 6 is in the form of a pin and is carried by two spaced angle plates 10 fixed to the door 25 E. The hinge pillar F is hollow and is provided in one wall 11 thereof with a slot 12 for receiving the shank B of the door check. The cushioning element C, washer D, and head A are located within the hollow pillar so that the cushioning 30 element C is engageable with the wall 11 to limit the outward swinging movement of the door when the latter is opened. However, it is apparent that the arrangement just described may be reversed, i. e., the anchorage member 6 may be secured to the hinge pillar F and the door E may be apertured to receive the shank B. In either instance the door E would be yieldably checked 35 when opened.

In Figures 5, 6 and 7 I have illustrated a slight 40 modification in which the washer D' is provided upon opposite sides of the slot 7a with two holes 20 and 21, and the head A' of the door check has open return-bent portions 22 and 23 that are received in said holes. Thus, the wire and washer 45 are locked together as a unit so that the device has increased strength and improved checking action. In this construction the cushioning element C' bears against the washer D' and the ends of the return-bent portions 22 and 23. 50

In Figures 8, 9 and 10 I have illustrated another modification in which the head A' of the device is substantially S-shaped. No washer is required or used with this construction as the head A' itself suffices. Actually the S-shape of 55

the head is such that added spring action to the cushioning element C² is afforded.

In each instance where wire is used it is to be understood that the wire is tempered spring steel.

5 Thus, from the foregoing it will be apparent that the door checks shown and described herein are simple yet strong and durable in construction and can be manufactured at a comparatively low cost. It also will be apparent that each form 10 shown includes means for effectively cushioning or absorbing shocks resulting from checking the swinging movements of the doors to which they are applied.

What I claim as my invention is:

15 1. A door check having a shank provided at one end with an eye and provided at the other end with a head, said shank being formed of wire return-bent upon itself, a yieldable cushioning element on said shank, and an abutment for 20 said element on said shank against said head and having means for holding the return-bent portions aforesaid of said wire in a predetermined relation to each other.

2. A door check having a shank provided at 25 one end with an eye and provided at the other end with a head, said shank being formed of wire return-bent upon itself, a yieldable cushioning element on said shank, and an abutment for said element on said shank against said head, said 30 abutment having a slot for receiving said eye and provided in opposite edges of said slot with notches for receiving the return-bent portions of said wire.

3. A door check having a shank provided at 35 one end with an eye for receiving an anchorage member and provided at the other end with a head, said shank, eye and head being formed from one piece of spring wire, a washer on said shank and having holes therein receiving portions 40 of said head, and a compressible cushioning element on said shank against said washer.

4. A door check having a shank and a cushioning element carried thereby, the shank being formed from a single strand of wire return-bent 45 upon itself and provided at one end with a head and provided at the other end with an eye, the head comprising laterally bent end portions of the wire, the eye comprising an opened part of the return-bend of the wire, and the cushioning 50 element being sleeved upon the shank adjacent said head.

5. A door check having a shank, and a cushioning element and an abutment therefor carried by said shank, the shank being formed from a 55 single strand of wire return-bent upon itself and provided at the free ends of the wire with a head, said head comprising laterally bent end portions of the wire, the eye comprising an opened part of the return-bend of the wire, the cushioning 60 element being sleeved upon the shank adjacent said head, the abutment being upon the shank between the head and cushioning element and serving also as a tie or coupling between the 65 return-bent portions of the wire at the free ends of the latter.

6. A door check having a shank, and a cushioning element and an abutment therefor carried by said shank, the shank being formed from a 70 single strand of wire return-bent upon itself and provided at the free ends of the wire with a head, said head comprising laterally bent end portions of the wire, the eye comprising an opened part of the return-bend of the wire, the cushioning 75 element being sleeved upon the shank adjacent said head, the abutment being upon the shank

between the head and cushioning element and being in the form of a substantially flat metal washer, said abutment having a slot therein for receiving the eye aforesaid and having other means for holding together the return-bent portions of the wire at the free ends of the latter. 5

7. A door check having a shank and a cushioning element carried thereby, the shank being formed from a single strand of wire and provided at one end with a head and provided at the other end with an eye, the head comprising open return-bent portions of the wire, and the cushioning element being sleeved upon the shank against the open return-bent portions aforesaid of the wire. 10

8. A door check having a shank, and a cushioning element and an abutment therefor carried by said shank, the shank being formed from a single strand of wire return-bent upon itself and provided at the free ends of the wire with a head, said head comprising open return-bent portions 20 of the wire, the cushioning element being sleeved upon said shank against the ends of the open return-bent portions aforesaid of the wire, and the abutment being upon the shank beside the cushioning element and having holes therein receiving the open return-bent portions aforesaid of the wire. 25

9. A door check having a shank and a cushioning element carried thereby, the shank being formed from a single strand of wire return-bent 30 upon itself and provided at one end with a head, the head comprising laterally-bent open return-bent portions of the wire, said open return-bent portions cooperating with each other to form in a plane substantially at right angles to the shank 35 the letter S, and the cushioning element being sleeved upon the shank against one side of the S.

10. A door check having a shank and a cushioning element carried thereby, the shank being formed from a single strand of wire return-bent 40 upon itself and provided at one end with a head, said head comprising open return-bent portions of the wire, said open return-bent portions being in a common plane substantially at right angles to said shank, and the cushioning element being 45 sleeved upon the shank against said open return-bent portions of the wire.

11. A door check having a shank and a cushioning element carried thereby, the shank being formed from a single strand of wire return-bent 50 upon itself and provided at the free ends of the wire with a head, the head comprising open return-bent portions of the wire, said open return-bent portions extending substantially at right angles to the shank, and the cushioning element 55 being sleeved upon the shank against said open return-bent portions.

12. A door check having a shank and a cushioning element, the shank being elongated in configuration and formed from a single strand of 60 wire, the cushioning element being formed of yieldable material and sleeved upon the shank, said cushioning element being compressible longitudinally of the shank, a portion of the wire 65 of the shank being bent laterally relative to the shank and serving to limit longitudinal movement of the cushioning element in one direction relative to the shank.

13. A door check having a shank and a cushioning element, the shank being elongated in configuration and formed from a single strand of wire, the cushioning element being formed of yieldable material and sleeved upon the shank, said cushioning element being compressible longitudinally of the shank, a portion of the wire 75

at one end of the shank being bent into the path of the cushioning element so as to limit longitudinal movement of said element in one direction relative to the shank.

- 5 14. A door check having a shank, a cushioning element, and an abutment for the cushioning element, the shank being elongated in configuration and formed from a single strand of wire, the cushioning element being formed of yieldable material and sleeved upon the shank, said cushioning element being compressible longitudinally of the shank, the abutment being on the shank at one side of the cushioning element, a portion of the wire of the shank being bent laterally relative to the shank and cooperating with the abutment to limit longitudinal movement of the cushioning element in one direction relative to the shank.
- 10
- 15

15. A door check having a shank, a cushioning element, and an abutment for the cushioning element, the shank being elongated in configuration and formed from a single strand of wire, the cushioning element being formed of yieldable material and sleeved upon the shank, said cushioning element being compressible longitudinally of the shank, the abutment being on the shank at one side of the cushioning element, a portion of the wire at one end of the shank being bent into the path of the abutment so as to cooperate with said abutment to limit longitudinal movement of said cushioning element in one direction relative to the shank.
